UNITED STATES PATENT OFFICE.

WESLEY SMITH, OF TOLEDO, OHIO, ASSIGNOR, BY DIRECT AND MESNE ASSIGNMENTS, TO CHARLES W. MORRIS, JR., TRUSTEE, AND CHARLES W. MORRIS, OF BOSTON, MASSACHUSETTS.

SMOKE-CONSUMING APPARATUS FOR BOILER AND OTHER FURNACES.

SPECIFICATION forming part of Letters Patent No. 479,767, dated July 26, 1892.

Application filed March 10, 1892. Serial No. 424,388. (No model.)

To all whom it may concern:

Be it known that I, WESLEY SMITH, of Toledo, in the county of Lucas and State of Ohio, have invented certain new and useful Improvements in Smoke-Consuming Apparatus for Boiler and other Furnaces, of which the following is a specification.

This invention has for its object to promote the combustion of fuel in fire-boxes or furnaces, and particularly the fire-boxes of steam-boilers, either stationary or locomotive.

The invention consists in the combination, with a furnace or fire-box, an air-compressor, and a conduit arranged to conduct compressed air to the fire-box and to subject said air to heat, of another conduit arranged to conduct external air at ordinary atmospheric pressure to the fire-box, the last-mentioned conduit being arranged to subject the air passing through it to heat and conduct such heated air to the point where the compressed air is delivered by the compressed-air conduit, the arrangement being such that the jet of compressed air acts somewhat on the principle of a jet of steam in an injector to induce a flow of air under ordinary pressure, the result being the supplying of a large volume of heated air to the fire-box.

The invention also consists in certain improvements relating to the construction and arrangement of the apparatus involved, all of which I will now proceed to describe and claim.

In the accompanying drawings, forming part of this specification, Figure 1 represents a side elevation and partial section of a locomotive provided with apparatus embodying my invention. Fig. 2 represents a section on line 2 2, Fig. 1. Fig. 2^a represents a section on line 2^a 2^a, Fig. 2. Fig. 3 represents a rear elevation of the fire-box of the locomotive shown in Fig. 1. Fig. 4 represents a section on line 4 4, Fig. 1. Fig. 5 represents a longitudinal section of the fire-box and a portion of the boiler. Fig. 6 represents a longitudinal section of the fire-box and casing of a stationary boiler, the boiler being shown in elevation. Fig. 7 represents an end view of the casing of the fire-box and boiler shown in Fig. 6.

The same letters of reference indicate the same parts in all the figures.

I have shown my invention in Figs. 1, 2, 3, 4, and 5 applied to the fire-box of a locomotive, and I will first describe said appliance with reference to said figures.

a represents the furnace or fire-box, which is or may be of the usual general construction.

b represents an air pump or compressor, which may be of any suitable construction and supported at any suitable point, said pump being herein shown as provided with an air-inlet *b'*.

*b*² represents a conduit for compressed air extending from the compressor *b* and communicating with the interior of the fire-box, so that the air which is compressed and set in motion by the pump *b* will enter the fire-box to promote the combustion of the fuel. The compressed-air conduit is arranged so that it will subject the air within it to heat before the air is delivered to the fire-box, so that the compressed air enters the fire-box in a heated condition. Any suitable means may be used to heat the air, and for the purposes of my invention it may be assumed that the conduit *b*² passes through a portion of the fire-box, although I prefer to provide a casing *b*³ on the exterior of the fire-box through which the compressed-air conduit passes, said casing being arranged to receive heat from the fire-box either by radiation from the wall against which the casing is placed or through flues⁴, connecting the interior of the casing *b*³ with the interior of the fire-box, as shown in Fig. 5. When the casing *b*³ is employed, I prefer to bolt or rivet it securely to one of the walls of the fire-box by means of flanges formed on said casing and to extend the conduit *b*² back and forth through the casing in a suitable number of return-bends, as indicated in dotted lines in Fig. 3, for the purpose of giving the conduit a sufficient exposure to the heat.

The conduit *b*² terminates at its delivering end in a nozzle *b*⁵, which is arranged to deliver a jet of compressed air to the fire-box, said nozzle being preferably of the form shown in Fig. 2^a, and arranged within the tapering or conical nozzle *c*, which forms the delivering end of the secondary air-conduit, which will

be presently described, said nozzles c and b^5 resembling in their relative arrangement and form an injector, the jet of compressed air delivered by the nozzle b^5 inducing a flow of 5 air through the nozzle c and through the secondary conduit.

In Figs. 1 and 2 I have shown the conduit b^2 as divided at b^6 , one division communicating with the casing b^3 at one end and the 10 other with the casing b^3 at the other end of the fire-box, so that compressed air is supplied simultaneously at both ends of the fire-box. In Figs. 2 and 3 I show each compressed-air conduit as provided with a series of nozzles 15 b^5 , so that air is delivered to the fire-box from each of the conduits in a series of jets or blasts. The supply of compressed air delivered by each nozzle may be regulated by means of a screw-threaded spindle b^7 . (Shown 20 in Fig. 2^a.)

For the purpose of supplying a large volume of heated air and of utilizing the force of the compressed air to induce a current of air at ordinary atmospheric pressure into the furnace, I provide a secondary air-conduit, which, 25 as already stated, terminates in a nozzle c , receiving the compressed-air nozzle b^5 . In the construction shown in Figs. 1, 2, 3, and 4 the secondary conduit comprises a tube c' , surrounding the smoke-pipe of the locomotive and adapted to receive air through perforations or other suitable openings inside the tube, a jacket or casing c^2 , partly surrounding the smoke-arch of the locomotive, and suitably 30 attached to the boiler or its casing, and pipes c^3 c^8 , extending from said jacket at opposite sides of the boiler to the nozzles c , there being as many of the latter as there are compressed-air nozzles b^5 . The tube c' , jacket c^2 , 35 pipes c^3 , and nozzles c constitute a conduit which receives air around the smoke-stack and conducts it downwardly along the heated surface of the smoke-stack, over the heated surface of the smoke-arch, and along the sides 40 of the boiler, so that each nozzle c delivers a supply of heated air to the space surrounding the delivering ends of the compressed-air nozzles b^5 . The jets of compressed air delivered by the nozzles b^5 induce a rapid flow of air 45 from the said secondary conduit, so that each nozzle c delivers to the fire-box a large volume of air, which results from a commingling of the compressed air furnished by the compressed-air conduit and the air furnished by 50 the secondary conduit, the entire volume being highly heated.

It will be seen that in the construction above described the air is heated without materially drawing on the resources of the fire-box, the air in the secondary conduit being heated entirely by the waste heat from the fire-box, while the air in the compressed-air conduit may be heated either by waste heat or by a comparatively small portion of the direct heat from the fire-box diverted into the casings b^3 . When the casings b^3 and the flue

b^4 , connecting the same with the interior of fire-box, are employed, I prefer to connect each casing b^3 with one or more of the nozzles c by means of one or more short tubes d , Fig. 3, 7^c said connections causing an upward draft through the casings b^3 and drawing sufficient quantities of the heated gases and products of combustion from the fire-box through the flues 75 b^4 into the casings b^3 to insure the heating of the air in the portions of the compressed-air conduits in said casings, it being understood that the products of combustion that enter the casings b^3 will pass through the connections d to the nozzles c and back into the fire- 80 box.

In Figs. 6 and 7 I show a stationary fire-box a' , arranged in suitable relation to a stationary boiler e . In this case the compressed air is supplied by a compressor b , which is connected by a pipe b^9 with one or more nozzles b^5 , arranged to deliver compressed air to the fire-box, said nozzles entering the front wall of the fire-box. The compressed-air conduit b^9 passes through the boiler-casing, so that it 90 is subjected to the heat from the fire-box and from the boiler, the compressed air being thus thoroughly heated before it reaches the nozzles b^5 . In this case the secondary air-conduit is composed of a pipe c^9 , which is open 95 to the atmosphere at c^{10} outside of the casing of the boiler, and passes through the said casing and along through the flue or passage, through which the heat passes through the fire-box to the chimney, and preferably over 100 the fire-box, as shown in Fig. 6, said pipe terminating in one or more nozzles or outlets c^{12} , arranged to deliver air at the delivering ends of the compressed-air nozzles b^5 . The conduit c^9 is preferably provided with two or more return-bends, as shown at c^{13} , in order to give 105 said conduit a greater area of surface exposed to the heat.

It will be seen that in this embodiment of my invention there is no difference in principle from that previously described, the action being essentially the same in both forms.

In Fig. 6 I have shown in the bridge-wall a^5 at the rear of the fire-box a chamber a^6 , which receives heated compressed air through 115 a branch pipe a^7 , connected with the compressed-air conduit, the compressed air entering the chamber a^6 being delivered to the fire-box through orifices a^8 in the bridge-wall.

I claim—

1. The combination, with a furnace or fire-box, of an air-compressor, a conduit connecting said compressor with the interior of the fire-box, and a secondary air-conduit arranged to conduct external air to the delivering end 125 of the compressed-air conduit, said secondary conduit being arranged to subject the air passing through it to heat, as set forth.

2. The combination, with a furnace or fire-box, of an air-compressor, a conduit connecting said compressor with the interior of the fire-box and arranged to subject the air pass-

ing through it to heat, and a secondary air-conduit adapted to conduct external air to the delivering end of the compressed-air conduit and arranged to subject the air passing

5 through it to heat, as set forth.

3. The combination, with a fire-box or furnace, of an injector comprising an inner and an outer nozzle, air-conduits connected with said nozzles and arranged to heat the air

10 passing through them, and an air-compressor

connected with the conduit communicating with the inner nozzle, as set forth.

In testimony whereof I have signed my name to this specification, in the presence of two subscribing witnesses, this 9th day of 15 March, A. D. 1892.

WESLEY SMITH.
